(57) **CLAIM**

The ornamental design for an ankle cuff for an exercise apparatus, as shown and described herein.

DESCRIPTION

FIG. 1 is a front, left side upper perspective view of an ankle cuff for an exercise apparatus showing my new design; FIG. 2 is a rear, right side upper perspective view thereof; FIG. 3 is a front, right side lower perspective view thereof; FIG. 4 is a rear, left side lower perspective view thereof; FIG. 5 is a front elevational view thereof; FIG. 6 is a rear elevational view thereof; FIG. 7 is a top plan view thereof; FIG. 8 is a bottom plan view thereof; FIG. 9 is a left side elevational view thereof; and, FIG. 10 is a right side elevational view thereof. The broken line showing of portions of the ankle cuff for an exercise apparatus form no part of the claim.

1 Claim, 10 Drawing Sheets
